FIG. 1 is a perspective view from the front of the module for storage rack showing a first embodiment of my new ornamental design;

FIG. 2 is a perspective view from the rear thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view from the front of a second embodiment of my new ornamental design, illustrating two modules in a stacked arrangement thereof;

FIG. 10 is a perspective view from the front of a third embodiment of my new ornamental design, illustrating two modules both placed sideways and in a stacked arrangement thereof;

FIG. 11 is a perspective view from the rear of FIG. 10 thereof; and,

FIG. 12 is a perspective view from the front of a fourth embodiment of my new ornamental design, illustrating two modules joined side by side thereof with one module placed sideways.
